UNITED STATES PATENT OFFICE.

NATHAN M. LOWER, OF PITTSBURGH, PENNSYLVANIA, ASSIGNEE TO LOCOMOTIVE STOKER COMPANY, A CORPORATION OF PENNSYLVANIA.

LOCOMOTIVE-TENDER.

1,257,369.

Specification of Letters Patent. Patented Feb. 26, 1918.

Application filed May 18, 1917. Serial No. 169,434.

To all whom it may concern:

Be it known that I, NATHAN M. LOWER, a citizen of the United States, and resident of Pittsburgh, county of Allegheny, and State of Pennsylvania, have invented certain new and useful Improvements in Locomotive-Tenders, of which the following is a specification, and which are illustrated in the accompanying drawings, forming a part

10 thereof.

The invention relates to tenders provided with fuel bins and with means for advancing the fuel from the rear end of the bin either to bring it within easy reach of the 15 fireman or to deliver it to a stoker mechanism.

The object of the invention is to provide improved means for controlling the motor which actuates the fuel-advancing means.

20 In devices of this character the motor is usually located at the rear end of the bin, either being housed within or mounted above the water tank; and it has been the usual practice to control such motor by means of 25 a system of levers operated by a hand crank or wheel located at the forward end of the bin. This lever system is ordinarily located below the body of the tender and its application has been attended with great diffi- 30 culty owing to the fact that this space is called upon to accommodate the brake mechanism of the vehicle. The present invention consists in providing in a tender fuel-advancing means controlled by means of a 35 valve so placed that it may be manipulated by the operator at the forward end of the tender.

A practical embodiment of the invention is hereinafter described, and is illustrated 40 in the accompanying drawings in which—

Figure 1 is a detail vertical longitudinal section of the tender;

Fig. 2 is a longitudinal sectional detail of the motor and a preferred form of distribut- 45 ing valve; and

Fig. 3 is a similar view showing a modified form of construction of the valve.

The tender is generally indicated by the 50 numeral 10, and is provided with a fuel bin 11 over the bottom of which reciprocates a pusher head 12, actuated by a fluid motor 13 housed within a casing 14 built into the water tank 15. As thus far described the device is substantially identical with that

forming the subject of a pending applica- 55 tion of Edward Ryan, Serial No. 104,142.

The motor 13 is of the single stroke re- 60 ciprocating type, being provided with a piston 16 and a distributing valve, the casing of which is designated 17. Fluid pressure, 65 such as steam or compressed air, is supplied to the valve casing from a suitable source of supply through a pipe 18, and an exhaust pipe 19 leads from this casing. The dis- 70 tributing valve is controlled by means of a relief valve 20, shown as positioned below the forward end of the tender and connected with the valve casing by a pipe 21 and op- 75 erated by a hand wheel 22 within easy reach of the operator, and connected with the valve 20 by means of a rod 23.

Steam or pressure ports 24, 25, lead from the valve casing to the opposite ends of the motor cylinder 13, and exhaust ports 26, 27, lead from the opposite ends of the cylinder 75 to the valve casing and enter the latter be- 80 tween the pressure ports. The exhaust ports are so positioned with reference to the cylinder that they are cut off or closed by the piston 16 before it reaches the cylinder 85 heads, in order to provide a cushioning action.

The distributing valve 28 is cylindrical in form and chambered, being open at one end, as shown at 29, its opposite end 36 being 85 closed and constituting a piston, there being adjacent this piston head lateral ports 30, 30, adapted to register, in one position of the valve, with the pressure port 24. The length of the valve is such that in the posi- 90 tion of Fig. 2 the pressure port 24 is uncov- 95 ered, the ports 30 being out of register with the port 25. The valve is provided with an annular peripheral cavity 31, adapted to alternately uncover the exhaust ports 26, 27, 95 and being at all times open to the exhaust pipe 19.

The valve is controlled by means of a piston 32, rigidly connected to it by means of a stem 33 and being of greater diameter 100 than the valve and reciprocating in a cylind- 105 rical extension 34 of the valve casing. The steam pipe 18 enters the casing between the piston 32 and the valve. A small by-pass 35, shown as extending through the piston 32, provides for an equalization of pressure upon both sides of the piston. As the pres- 110 sure at the valve side of the piston 32 reacts

between this piston and the piston head 36, the effective preponderance of area on the opposite side of the piston 32 causes the shifting of the valve to the position shown 5 in Fig. 2.

The relief valve 20, which may be of any suitable form of construction, is of greater capacity than the passage 35, and when opened exhausts the steam from the outer 10 end of the cylinder 34, whereupon the pressure upon the opposite face of this piston moves it to the right and shifts the valve to close the pressure port 24 and exhaust port 27 and open the pressure port 25 and ex- 15 haust port 26. The motor piston 16 is there- upon driven to the opposite end of the cylinder, and there remains until the relief valve 20 is closed. As soon as the pressure is again 20 equalized at the opposite sides of the piston 32, the valve is moved to the left, the position shown in Fig. 2, and the motor piston is returned to the position there shown.

In order to advance the pusher head 12 from the position shown in Fig. 1, the operator 25 opens the relief valve 20 by manipulating the hand wheel 22, and as soon as the advance stroke is completed he closes this valve and the pusher head is withdrawn under the fuel in readiness for the next ad- 30 vance stroke.

In the modification shown in Fig. 3, the distributing valve 37 is shown as having a solid body with an annular exhaust cavity 38, the pressure ports 24, 25, communicating 35 with the motor cylinder being alternately uncovered by the body of the valve and the valve casing 39 being provided with a duct 40, into which the steam pipe enters and which leads to both ends of the casing. The 40 controlling piston 41, while of greater diameter than the valve, is smaller than the piston 32, in the construction illustrated in Fig. 2. A spring 42, interposed between the outer face of this piston and the head of the 45 cylinder within which it reciprocates, insures the prompt movement of the distributing valve when the relief valve 20 is closed, and pressure is equalized on both sides of the piston through the by-pass 35. The 50 steam pipe 18 and the pipe 21 leading to the relief valve 20 may be located in any available space without interfering with any of the other mechanism of the tender, such as the draft gears and brake devices. 55 In its broader aspects, the invention is not

concerned with the details of construction of the pusher head, the motor and its distributing valve, and the relief valve, and various changes may therefore be made from the structures disclosed without departing from it. 60

I claim as my invention—

1. In a locomotive tender having a fuel bin, in combination, a reciprocating fuel pusher in the bin, a single-stroke fluid motor 65 for actuating the pusher, a fluid-controlled distributing valve normally open to one end of the motor cylinder, and a relief valve for controlling the distributing valve.

2. In a locomotive tender having a fuel 70 bin, in combination, a reciprocating fuel pusher in the bin, a single-stroke fluid motor for actuating the pusher, a fluid-controlled distributing valve normally open to one end of the motor cylinder, and a valve for controlling the distributing valve. 75

3. In a locomotive tender having a fuel bin, in combination, a reciprocating fuel pusher in the bin, a single-stroke fluid motor for actuating the pusher, a fluid-controlled 80 distributing valve normally open to one end of the motor cylinder and having a normally balanced actuating piston, and a vent valve for relieving the pressure on one side of the piston. 85

4. In a locomotive tender having a fuel bin, in combination, a reciprocating fuel pusher in the bin, a single-stroke fluid motor for actuating the pusher, a distributing valve of the piston type, a controlling piston 90 reciprocating in the casing of the valve and connected to the valve, a normally open pipe leading from a source of pressure to the casing of the valve and communicating therewith between the valve and the piston, 95 a by-pass for delivering pressure to the opposite side of the piston, and a vent valve for relieving pressure transmitted through the by-pass.

5. In a locomotive tender having a fuel 100 bin, in combination, a pusher head reciprocable in the bin for advancing fuel, a single-stroke actuating motor back of and connected with the head, a pressure-controlled distributing valve for the motor normally open to one end of the motor cylinder, and a relief valve located at the forward end of the tender for controlling the distributing valve. 105
